(57) **CLAIM**

I claim the ornamental design for a drinking cup stabilizer, as shown and described.

DESCRIPTION

FIG. 1 is a top perspective view of a drinking cup stabilizer showing my new design.

FIG. 2 is a bottom perspective view thereof.

FIG. 3 is a bottom plan view thereof.

FIG. 4 is a top plan view thereof.

FIG. 5 is a side view thereof, the opposite side being a mirror image.

FIG. 6 is a front view thereof; and,

FIG. 7 is a rear view thereof.
